CLAIM

(21) Appl. No.: **29/132,988**

The ornamental design for a multi-function portable power system, as shown and described.

(22) Filed: **Nov. 21, 2000**

DESCRIPTION

(51) **LOC (7) Cl.** **13-02**

FIG. 1 is a top plan view of the multi-function portable power system showing our new design;

(52) **U.S. Cl.** **D13/110**; D13/107

FIG. 2 is a bottom plan view of the design shown in FIG. 1; FIG. 3 is a right side elevational view of the design shown in FIG. 1;

(58) **Field of Search** D13/106, 107,

FIG. 4 is a left side elevational view of the design shown in FIG. 1;

D13/108, 110; 320/105–115; 307/150, 64

FIG. 5 is a rear elevational view of the design shown in FIG. 1;

(56) **References Cited**

FIG. 6 is a front elevational view of the design shown in FIG. 1; and,

U.S. PATENT DOCUMENTS

FIG. 7 is a perspective view of the design shown in FIG. 1.
